UNITED STATES PATENT OFFICE.

MICHAEL B. GREEN, OF MEMPHIS, TENNESSEE.

OIL-PRESS.

1,348,870.

Specification of Letters Patent. Patented Aug. 10, 1920.

Application filed March 6, 1920. Serial No. 363,755.

To all whom it may concern:

Be it known that I, MICHAEL B. GREEN, a citizen of the United States, and resident of Memphis, in the county of Shelby and State of Tennessee, have invented certain new and useful Improvements in Oil-Presses, of which the following is a specification, reference being had therein to the accompanying drawing.

10 The general object of this invention is to improve oil presses commonly used and especially to provide novel mat supports to be superposed and moved vertically in the press frame. Neither the frame nor the 15 means for applying pressing power is shown, since substantially the common construction may be employed.

It has been common to form the body of a mat support of parallel spaced bars upon 20 which the mat or bag containing oil-yielding material is laid and subjected to very heavy pressure, while its warp threads are parallel to the spaced bars between which the expressed oil passes downward. To allow oil, 25 at the outset, to escape rapidly, the spaces between the bars are comparatively wide. The woof threads which alone cross these passages are subjected to such strain over, or in, the passages that they are often ruptured, especially if used repeatedly as they 30 must be, practically, to save expense. Some lessening of this evil has been brought about by narrowing the spaces between the bars and at the same time cutting in the sides of 35 the bars many narrow slots perpendicular to their axes. The use of initially separate bars has advantages over forming channels in a continuous metal plate, and when a plate is used it is advisable to make it thin 40 and obtain the indispensable strength by bars below the plate.

This invention involves the use of bars without a plate above them and these bars are placed in lateral contact, rigidly united, 45 and provided with lateral oil channels into which vertical oblique slots open.

In the accompanying drawings,

Figure 1 is a side sectional elevation of one of the mat supports with parts of another above.

Fig. 2 is a plan view of a part of the same structure.

Fig. 3 is a detail view showing in bottom plan parts similarly lettered in other figures.

55 Fig. 4 is a detail view of a device for

safely detaching the mat from the next superposed support.

In these figures, 10 represents a bed member of the lower support, 11 a set of parallel bars which are rigidly held in contact by a 60 rivet, or bolt, 12 and rest upon said bed. The outer bars have cam-like outer faces 11', below mentioned, and the intermediate bars, duplicates of each other, have lateral faces shown as plane except for grooves or 65 channels 13 therein extending from end to end of the bars and gradually falling slightly. The grooves in adjacent bars register so as to form a single symmetrical slightly inclined channel. Each bar has in 70 its upper side many parallel very narrow vertical slots 14 preferably inclined at an angle of 45° and extending to the medial line of the bar and downwardly to intersect the corresponding channel 13, and the channels 75 on the meeting sides of adjacent bars are alined, while the slots on the next pair although parallel to those of the adjacent pairs are in lines midway between the others as shown.

80 The mats lie upon the supports just described and between curved steel plates 15 extending from end to end of the supports and having their upper edges loosely engaged in shallow slots 16 in the bed 10' of 85 the next support above, the plates being held up by bolts 17 passing through slots 18 in lugs 19 upon the plates 15 and working in heavy brackets 20 bolted to the bed 10' above. The plates are pressed inward 90 by springs 21, adjusted by bolts 22 working in lugs on the brackets 20. These curved plates thus primarily pressed against the faces 11' of the outer bars 11 follow those faces as the mats are compressed until the 95 limit of compression is nearly reached when their lower edges are pushed outward by the outwardly turning faces 23 of the bars, loosening them from the thin oil cake, opening a narrow channel for the escape of oil, 100 and allowing the supports to move freely to initial position, so far as these plates are concerned.

105 It is found that the mats now compressed to thin and very dense cakes adhere somewhat strongly to the plates 10' above, and it has been usual to detach them by means of a thin bar having a chisel-like end. In thus detaching them the fabric is often torn, even when care is exercised by employees. 110

To remedy this evil the lower side of each base 10, 10' is channeled to receive a thin bar 26 attached to a row of plungers 27 having upwardly convex heads 28 projecting into a shallow channel 29 in the upper side of the base and held up by a spring 30. The bars 11 immediately above this channel 29 are preferably cut away to form a channel 31. When the mat is to be loosened from the bed 10' a flat metal bar is forced into the slots 29, 31 and as it passes over the heads 28 the thin bar 26 is forced directly downward pulling the mat from the base.

It is to be observed that the construction set forth combines the advantages of oblique slots, primarily independent bars, and numerous very short and narrow slots.

What I claim is:

1. In an oil press, a mat support having its body made up of rigidly united bars laterally contacting at their upper sides in the same plane and having their meeting faces provided with registering grooves forming oil passages from end to end of the bars, each bar having in its upper side narrow oblique grooves extending downward on each side into said passages, and from the lateral margins of the bars approximately to their medial lines.
2. In an oil press, the combination with mat supports to be superposed, of plates pivotally engaged with a support above and fitting respectively against opposite lateral faces of the next support below to support the margins of the intermediate mat, and means whereby the plates are moved outward from the mats as the limit of compression is reached.
3. In an oil press, the combination with a plane mat support having a bar extending across its lower face in position to make contact with a mat of the next lower support in the press frame, and means for at will forcing this bar downward after the completion of compression to detach the mat from the support above.
4. The combination with a plane mat support to act as one of a series of similar verti-

cally movable supports superposed in a press frame, and provided with a recess in its face, of a member lying in said recess, a spring resisting outward movement of said member and arranged to have its action overcome by a suitable manually used device urging the member outward, whereby said member detaches the mat from the support in which the member lies.

5. The combination with mat supports to be superposed and moved vertically in a press frame while separated by the mats to be acted upon, of plates normally closing on two opposite sides the spaces in which the mats lie, each plate being pivotally engaged with the support above and spring pressed against the lateral walls of the support below, and means automatically moving each plate outward as the supports near the limit of their pressing movement.

6. The combination with two spaced superposed mat supports and marginal plates laterally closing the space between the supports and having their upper margins pivotally engaging the upper support, springs normally pressing the lower sides of said plates against the corresponding sides of the next lower support, said corresponding sides being adapted to swing the plates outward when they descend beyond a certain point.

7. The combination with mat supports to be superposed in a press with mats intervening and having the lower members provided above and below with registering shallow grooves extending from side to side, of a plate normally filling the lower groove and provided with vertically sliding studs extending into the upper groove and having upwardly convex upper ends, and springs resisting downward movement of the studs; whereby a suitable tool or bar being forced into the upper groove depresses the studs successively and by depressing their plate forces the mat away from the support above.

In testimony whereof I hereunto affix my signature.

MICHAEL B. GREEN.
